UNITED STATES PATENT OFFICE.

WILLIAM B. GRIMES, OF OPE, ALABAMA.

WAGON BRAKE.

Application filed February 6, 1926. Serial No. 86,497.

My present invention pertains to wagon brakes, and contemplates the provision of a peculiar and advantageous construction whereby draft animals are utilized to apply brake shoes to the front wheels of a wagon, the said brake shoes being applied when the draft animals pull backwardly on the tongue of the wagon as when a grade is being descended.

10 Other objects and practical advantages of the invention will be fully understood from the following description and claims when the same are read in connection with the drawings, accompanying and forming part 15 of this specification, in which:—

Figure 1 is a plan view of so much of a wagon construction as is necessary to illustrate the preferred embodiment of my invention.

20 Figure 2 is an enlarged longitudinal vertical central section of the same.

Figure 3 is a fragmentary inverted plan view hereinafter explicitly referred to.

25 Similar numerals of reference designate corresponding parts in all of the views of the drawings.

The structure illustrated comprises among other elements a front axle 1, equipped with ground wheels 2, and fixedly connected at 3 to hounds 4, the said hounds 4 being connected together at an intermediate point through the medium of a transverse bar 5, and being connected together at their forward spaced ends by upper and lower plates 30 6 and 7. The said plates 6 and 7 are provided at 8 and 9, respectively, with coincident longitudinal slots as shown in Figures 2 and 3. Connected at 10 with the cross bar 5 superposed upon the hounds 4 and extending forwardly from the said bar 5 is a metallic bar 11 that is longitudinally slotted as designated by 12. Slidable longitudinally in the longitudinal guideway formed between the forward portion of the 40 hounds 4 and also between the plate 6 and 7 is a tongue or pole 13 to the forward portion of which draft animals are hitched in the conventional manner or in any other manner compatible with the purpose of my 45 invention which involves the rearward movement of the tongue or pole 13 when pull is exerted on said tongue or pole 13 as when a wagon is descending a hill. The said tongue or pole 13 is equipped with a removable pin 14, flexibly connected at 15 to the tongue or pole. It will also be apparent

from Figure 2 that the tongue or pole 13 is sheathed with appropriate metal at 16, and that a vertical aperture 17 is formed in the tongue and also in the lower and upper portions of the metallic sheathing, said vertical aperture 17 being designed to receive the pin 14 under certain conditions as hereinafter pointed out. Superposed upon the upper plate 6 and movable thereon longitudinally of the wagon is a brake beam 18, the said beam 18 being provided adjacent to its ends with appropriately spaced shoes 19, arranged forward of the peripheral portion of the ground wheels 2. The said beam 18 is interposed between the bar 11 and the plate 6 and is fixedly connected to the tongue or pole 13 through the medium of a vertical bolt 20, the said bolt 20 extending through the slot 12 of the bar 11, through the brake beam 18 and through the slots 8 and 9 in the plates 6 and 7, and being provided at its upper end with an appropriate head and washer and at its lower end with an appropriate nut and washer. It 30 will be apparent from the foregoing that when forward pull is exerted on the tongue or pole 13, the brake shoes 19 will be maintained out of engagement with the ground wheels 2, and hence my improvement will not interfere in any measure with the forward movement or control of the wagon. When, however, rearward pull is exerted by the draft animals on the tongue or pole 13, the beam 18 moving rearwardly with the tongue or pole 13 will bring about the powerful application of the brake shoes 19 to the wheels 2, and the greater the rearward draft on the tongue or pole 13 the more powerfully will the brake shoes 19 be held to the peripheral portions of the wheels 2 for the efficient braking of the wagon. When it is not desired to apply the brake shoes 19 to the front wheels 2 of the wagon, it is simply necessary for the person in authority 35 to dispose the pin 14 in the aperture 17 inasmuch as when this is done, the pin 14 by bringing up against the forward ends of the plates 6 and 7, will effectively prevent rearward movement of the tongue or pole 13 40 sufficiently far to carry the brake shoes 19 into engagement with the wheels 2.

Notwithstanding the capacity of function ascribed to my improved construction, it will be appreciated that the construction as disclosed is simple and inexpensive, and as a whole is well adapted to withstand the

rough usage and the shock and jars to which wagon appurtenances are ordinarily subjected.

I have entered into a detailed description 5 of the construction and relative arrangement of the parts embraced in the present and preferred embodiment of my invention in order to impart an exact understanding of the said embodiment in all of its details. I 10 do not desire, however, to be understood as limiting myself to the precise construction and relative arrangement of parts as disclosed, my invention being defined by my appended claims within the scope of which 15 changes in construction and in arrangement may be made without departure from my invention.

Having described my invention, what I 20 claim and desire to secure by Letters-Pat- ent, is:—

1. In a front wheel wagon brake and in combination, a front axle equipped with ground wheels, hounds connected to and extending forwardly of said front axle, plates 25 arranged above and below and connected to the forward portions of the hounds and having coincident longitudinal vertical slots at points opposite the forward portions of the hounds, a longitudinal bar connected 30 with the hounds at an intermediate point in the length thereof and provided with a longitudinal vertical slot in its forward portion, a tongue movable longitudinally between the hounds and also between the said 35 slotted plates, said tongue having metallic sheathing in opposed relation to the said slotted plates and also having a vertical aperture, a pin flexibly connected with the tongue and adapted to be removably inserted in said apertures to prevent operative rearward movement of the tongue, a transverse brake beam movable upon the upper slotted plate and interposed between said plate and the longitudinally slotted for- 40 ward portion of the said bar on the hound, and a bolt extending through the said beam and also to the longitudinal slot in the said bar and through the tongue and also through the longitudinal slot in the lower and upper 45 plates, and movable forwardly and rearwardly with the said beam.

2. In a brake construction for the front wheels of a wagon and in combination, a front axle, ground wheels carried thereby,

hounds connected to and extending forward- 55 ly of said axle and having a space between their forward portions, lower and upper longitudinally slotted plates fixed to the forward portions of the hounds, a tongue movable longitudinally between the forward por- 60 tions of the hounds and also between the said slotted plates, a longitudinal bar connected with the hounds and having a forward lon- 65 gitudinally slotted portion overhanging and spaced above the uppermost slotted plate, a transverse brake beam movable rearwardly and forwardly between the slotted portion of 70 said bar and the uppermost slotted plate and equipped with brake shoes opposed to the wheels, and means connecting the tongue and said transverse beam and disposed and mov- 75 able longitudinally of the wagon in the said slots of the longitudinal bar and the plates above and below the hounds.

3. In a brake construction for the front 75 wheels of a wagon and in combination, a front axle, ground wheels carried thereby, hounds connected to and extending forwardly of said axle and having a space be- 80 tween their forward portions, lower and up- 85 per longitudinally slotted plates fixed to the forward portions of the hounds, a tongue movable longitudinally between the forward portions of the hounds and also between the said slotted plates, a longitudinal bar con- 90 nected with the hounds and having a forward longitudinally slotted portion overhanging and spaced above the uppermost slotted plate, a transverse brake beam movable rear- 95 wardly and forwardly between the slotted portion of said bar and opposed to the wheels, and means connecting the tongue on said transverse beam and disposed and mov- 100 able longitudinally of the wagon in the said slots of the longitudinal bar and the plates above and below the hounds; the said tongue being provided in advance of the slotted plates with a vertical aperture, and being equipped with a pin flexibly connected with and removably socketed in the tongue and 105 adapted when disposed in said aperture to bring up against the forward ends of the slotted plates and prevent rearward move- ment of the tongue with respect to the hounds.

In testimony whereof I affix my signature.

WILLIAM B. GRIMES.
